UNITED STATES PATENT OFFICE.

THOMAS B. FERGUSON, OF NEW YORK, N. Y.

LIQUID-FUEL BURNER.

1,111,448.

Specification of Letters Patent.

Patented Sept. 22, 1914.

Application filed January 5, 1912. Serial No. 669,620.

To all whom it may concern:

Be it known that I, THOMAS B. FERGUSON, a citizen of the United States of America, and a resident of Brooklyn, city of New York, county of Kings, and State of New York, have invented certain new and useful Improvements in Liquid-Fuel Burners, of which the following is a specification.

This invention relates to burners for kerosene and other liquid hydrocarbons and is particularly intended for producing a heating flame; the burner being therefore adapted for use in heaters of various types, stoves, furnaces, ranges, etc.

The improved burner herein described comprises a fuel-heating tube into which the oil is introduced under pressure, said tube passing above the burner proper, so as to be subjected to heat from the flame, and thence passing downwardly into the burner proper so that the heated oil, or the gas formed by the heating of the oil in such tube, may issue from the burner orifice.

As burners employing fuel-heating tubes such as described have been constructed heretofore, much trouble has been experienced from formation of carbon or tar deposits in the fuel-heating tube, due to the fact that such tubes in practice have been heated to too high a temperature.

In the burner herein described direct contact of the flame with the principal portion of the fuel-heating tube is avoided, such tube being, in fact, so located that it is surrounded by a downwardly moving current of air which, as compared with the flame, is relatively cool; the fuel-heating tube being heated in the main by heat radiated from the flame, instead of by direct contact with the flame.

In the burner herein described the initial portion of combustion takes place in a chamber which is substantially closed, except for suitable air inlet and flame outlet openings, the shape of this chamber, and the location of the flame outlet opening, being such that the flame is spread outwardly, being, therefore, a hollow substantially cylindrical flame of considerable diameter.

My invention consists in the features hereinafter particularly described and set forth in the appended claims.

The objects of my invention are to produce a relatively simple and inexpensive and very effective burner of the class de-

scribed; to avoid formation of deposits in the fuel-heating tube; and to so design the burner that its flame shall be little disturbed by external air drafts, so that the burner may be used, when desired, in the open air.

Other objects of my invention will appear hereafter.

I will now proceed to describe my invention with reference to the accompanying drawings, and will then point out the novel features in claims.

In said drawings: Figure 1 shows a central vertical section of one form of my improved burner, mounted upon a suitable tank; Fig. 2 shows a side elevation of my improved burner looking from the right hand side of Fig. 1, portions of the burner being broken away and other portions shown in section; Fig. 3 shows a horizontal section of the burner on the line $\alpha-\alpha$ of Fig. 2; Fig. 4 shows a horizontal section of burner on the line $\gamma-\gamma$ of Fig. 2.

In the drawings 1 designates a pressure tank containing the kerosene or other fuel for the burner and 2 a pipe for conveying the oil from tank 1 to the fuel-heating tube 3. The upper portion of the tank 1 is, customarily, an air space containing air or other gas under pressure sufficient to force the oil up into the fuel-heating tube. Pipe 2 terminates in an internally threaded boss 4 of a burner base 5; and a threaded connection 6 projects outwardly from the opposite side of the bore of the boss 4, and is connected to one end of the fuel-heating tube 3. The other end of the said fuel-heating tube is connected to a connection 7 screwing into a suitable aperture in base 5 which leads to a gas conduit 8 provided in burner base 5. A conduit 9 leads from this gas conduit 8 and is provided at its top with a burner tip 10 having in it a burner orifice 11. A needle valve 12 regulates the flow of oil into the fuel-heating tube and so regulates the flow of gas to the burner orifice 11.

The space 13 immediately above the burner orifice 11 constitutes an initial combustion space, this space being inclosed by a two part shell 14-15, member 14 having in it suitable air inlet openings 16 and member 15 having near its top a gas exit opening 17, such opening 17 being preferably somewhat to one side, as indicated in Fig. 1. The section 14 of the said shell has projecting from it a platform 18. Above the member 15 of

the initial-combustion chamber shell is a bell-shaped member 19 constituting a flame-guard and flame-deflector. This member 19 is supported by screws 20 of the platform 18, by means of which screws the height of the member 19 with reference to the member 15 may be adjusted as desired. The interior of this member 19 of course constitutes a further combustion chamber. Upon this member 19 rests a further flame deflector and draft-director, 21, which member 21 in practice is of two-part construction, its two parts being secured together by means of bolts 22, said member 21 resting upon the flame guard 19. This flame-deflector 21 has a depending skirt 23. The flame, issuing from the orifice 17 of burner shell 15, is directed downwardly and as a flame annulus, by deflector 19, and issues through the annular space between the lower edge of the deflector 19 and the platform 18, spreading horizontally until it passes the lower edge of the skirt 23, and then rising more or less directly. The rising flame annulus thus formed incloses the fuel-heating tube 3 but does not, ordinarily, directly contact with said fuel-heating tube, except where the legs of the fuel heating tube pass transversely across the path of the flame, opposite the lip at the bottom of deflector 19; and these two points of contact of the flame of the fuel-heating tube are extremely short and moreover conditions are such at these points that contact of the flame with the fuel-heating tube is not harmful. In the space within this annular flame there is a downwardly flowing current of air, induced by the gas itself, in its passage between shell 14—15 and flame-deflector 19, the deflector 19 having in it air admission ports 24 through which this downwardly flowing current of air passes to mingle with the outgoing flame. The flame deflector 19 has at its top a boss 25, externally grooved or corrugated, as is the upper surface of said deflector 19; and the portion 26 of the deflector 21 which surrounds this boss is spaced away therefrom and flares outwardly and upwardly, forming therefore, as to the downwardly flowing air current, a contracting passage leading such air current to the air admission openings 24. Within the deflector 19 is a secondary deflector 27, above the flame orifice 17, and which receives the first impact of the flame; deflector 27 being removably secured to deflector 19, as illustrated, so that it may be replaced from time to time should occasion for replacement arise; and in this secondary deflector 27 there are air ports 28 substantially opposite ports 24 in deflector 19. Through these ports 28 a considerable proportion of the air will pass into direct contact with the flame issuing through opening 17.

65 The platform 18 is provided with various

draft openings, 29, and 30, and beneath said platform 18 there is a trough 31 adapted to contain water; said trough being supported by the platform 18 and being also provided with draft ports 31^a substantially registering with the draft ports 29 of platform 18. The water contained in this trough is vaporized by heat radiated from the flame and by heat conducted through the metal structure of the burner, the water vapor thus produced mingling with the flame and materially modifying the character of the flame, producing a much hotter flame than would otherwise be obtained, and one which is much less likely to deposit carbon. Water 80 is supplied to this trough through a pipe 32, Fig. 2.

The platform 18 is supported from the top of tank 1 by a number of legs 33. The flame space is surrounded by a series of suitably arranged concentric perforate flame-guards 34, 35 and 36, above which is a grid 37 upon which particles to be heated may be placed, this grid being supported from the platform 18 by posts 38.

The action of this burner, supposing it to be already in operation, is as follows: Oil, forced upward from the tank 1 to pipe 2, by the pressure of the compressed air or other gas in said tank, passes into the fuel-heating tube 3, and in passing through said tube is subjected to heat radiated inward from the hollow cylindrical flame surrounding said tube and passing up through the space between flame-guards 34 and 36; the radiation 95 of such heat being modified as to its influence on the fuel-heating tube, by the downwardly flowing current of relatively cold air which enters the contracting top of the deflector 21, and thence passes into the 100 draft ports 24. Where the sides of the fuel-heating tube pass through the flame, as they do just above platform 18 they are transverse to the path of the flame, the portion of the tube so passing through the flame being 110 therefore, very small. Moreover, in one of such portions of the fuel-heating tube, the oil is still too cold to be vaporized, whereas in the other such portion of the tube the oil exists in the form of a vapor, therefore the 115 direct action of the flame on these small portions of the tube will not cause formation of deposits in either case. By reason of the substantial freedom of the fuel-heating tube from actual contact with the flame and by 120 the reason of the modifying action of this downwardly flowing air current, the fuel-heating tube is maintained at a relatively moderate temperature which, however, is sufficiently high to thoroughly vaporize the 125 oil, or to heat the oil to a temperature such that when it emerges from the burner orifice 11 it immediately turns into vapor, but without causing "cracking" of the oil, such as results in formation of carbon or tar deposits. 130

The oil vapor produced in the fuel-heating tube passes into the gas conduit 8 of the burner base 5 and thence up through conduit 9, emerging through the burner orifice 11. Owing to the pressure maintained within the fuel-heating tube 3, the gas issues from the burner orifice 11 with great velocity, drawing in air through the air ports 16. Combustion begins ordinarily within the structure 14-15 and as the partly burned gases are deflected downward by the deflectors 27 and 19, they draw in air through ports 24 and 28, which air assists in maintaining combustion of the gases. The flame gases pass beneath the lower edge of the deflector 19, and below the edge of the skirt 23 of the deflector 21, and thence pass more or less directly upward in the form of a flame annulus. During the progress of the gases as described, considerable water vapor, resulting from evaporation of water in the trough 31, is mingled with them, modifying the flame and increasing its heating power. The heat thus produced beneath the grid 37 is very intense and, being well diffused, is well calculated to heat rapidly and efficiently objects placed upon this grid 37. At the same time, the flame is so protected at its point of inception by the structure 14-15-19, and thereafter by the platform 18, deflector 21, and flame guards 34, 35 and 36, that it is very little affected by external air drafts, even by strong winds. The flame is readily regulated by means of the needle valve 12. Variation of character of the flame, through a considerable range, may also be obtained by varying the height of the flame deflector 19, with respect to the platform 18, by turning up or down the screws 20. This adjustment must of course be effected while the burner is not in use. Owing to the fact that flame orifice 17 is somewhat to one side of the axis, the flame has a peculiar rotary motion within the burner which motion helps to insure thorough mixture of the air with the combustible gases. The frequent changes in direction of the flame, such as caused by deflector 19 and skirt 23, and the turning of the flame downward by deflector 19, also help to insure thorough mixture of the air with the combustible gases.

For starting the burner into action, that is to say, for heating up the structure 14-15-21 and the fuel-heating tube 3, I employ a starting burner 39 illustrated particularly in Figs. 2 and 4 and which consists of a Bunsen tube 40 having air ports 41 and leading from a base 42 to which oil is admitted, from the tank 1, by means of a pipe 43. The oil thus admitted passes through a vaporizing tube 44 back into base 42 and thence out through the Bunsen tube 40. The outer end of this Bunsen tube is perforated, as shown particularly in Fig. 4, such

perforations constituting other air admission ports. Beneath the Bunsen tube is arranged a tray 45, preferably containing asbestos or other absorbent, into which tray may be poured a few drops of alcohol or similar volatile combustible, at starting, and this alcohol or other combustible ignited. The flame thus produced will heat the small starting burner 39 very quickly and this burner may then be started in operation by opening the needle valve 46, whereupon the starting burner will project into the structure 14-15 a flame sufficient to heat up that structure and the fuel-heating tube 3 very rapidly. When this fuel-heating tube 3 has been sufficiently heated, the main burner may be started by opening needle valve 12. The pipe 43, supplying fuel to the starting burner, is connected at its lower end to two small pipes 431 and 432, of which 431 terminates in the air space in the upper portion of tank 1, while pipe 432 extends down into the body of liquid in said tank. As a result, both air and oil are supplied by tank 1 to pipe 43, air being supplied through pipe 431 and oil through pipe 432. By reason of this supply of air as well as oil through pipe 43, very little heating of the starting burner is required before the vapor escaping from said burner will ignite.

The main burner herein described is capable of making gas in considerably greater quantity than required for the burner itself; and since it is frequently desirable to maintain an illuminating flame or other small flame in addition to the main flame of the burner, in such cases I provide a valve 46 connecting with the gas conduit 8 of the burner base and communicating with a pipe 47 leading to any suitable point, as for example to a valve 48 to which a suitable burner may be secured. A pipe 471 leads back from pipe 47 to the interior of flame deflector 19, the inner end of this pipe 471 being closed by a plug 472, except for a very small hole through such plug. This pipe 471 serves to lead into the main flame liquid which may accumulate in the upper portion of pipe 47 and in valve 48, due to condensation or other causes.

The burner base 5 is provided with a trough 49 to receive any possible drip from the main burner. Said burner base 5 is further provided with a cleaning rod 50, within gas conduit 9 and mounted upon the end of a screw 51 passing through a suitable stuffing box of base 5. Normally, this cleaning rod 50 is backed away from burner orifice 11; but if for any reason burner orifice 11 becomes obstructed the cleaning rod may be forced through such orifice by means of screw 51 so clearing such orifice of any obstruction. The end of the screw 51, being adapted to seat against the lower end of tube 9, forms a valve, supplemental to valve 12, 130

for regulating the action of the burner; and the rod 50 forms a further supplemental valve, since when in, or in close proximity to, orifice 11, it restricts flow through that orifice.

5. In a companion application filed January 5, 1912, Sr. No. 669,619, I have illustrated and described a burner embodying the broad invention of the burner of this case, but differing in certain features of construction.

10. What I claim is:—

1. A liquid fuel burner comprising in combination a burner proper, comprising flame-deflecting means adapted to convert the flame of said burner into a widely-spread flame annulus, a fuel-heating tube the major portion of which passes through the space included inside such flame annulus when the burner is in operation, and connected to the burner proper to supply gas thereto, all portions of said tube which may normally be in the path of the flame being arranged transversely to such path, and means for supplying liquid fuel to said fuel-heating tube.

2. A liquid fuel burner comprising in combination a burner proper, comprising flame-deflecting means adapted to convert the flame of said burner into a widely-spread flame annulus, a fuel-heating tube the major portion of which passes through the space included inside such flame annulus when the burner is in operation, and connected to the burner proper to supply gas thereto, all portions of said tube which may normally be in the path of the flame being arranged transversely to such path, and means for supplying liquid fuel to said fuel-heating tube, said burner further comprising means for producing a downdraft of air within the space surrounded by such annulus and in the vicinity of the portion of the fuel-heating tube passing through such space.

3. A liquid fuel burner comprising in combination a burner proper comprising flame-deflecting means arranged to cause the flame to spread out nearly horizontally and thence to pass upward in the form of an annulus, a return-bend fuel-heating tube the major portion of which is located within the space inclosed by such annulus when the burner is in operation, the two legs of such tube passing through the horizontal portion of the flame transversely, said fuel-heating tube connected at one end to the burner proper; and means for supplying liquid fuel to the other end of such fuel-heating tube.

4. A liquid fuel burner comprising in combination a burner proper comprising flame-deflecting means arranged to cause the flame to spread out nearly horizontally and thence to pass upward in the form of an annulus, a return-bend fuel-heating tube the major portion of which is located within the

space inclosed by such annulus when the burner is in operation, the two legs of such tube passing through the horizontal portion of the flame transversely, said fuel-heating tube connected at one end to the burner proper, and means for supplying liquid fuel to the other end of such fuel-heating tube, said burner further comprising means for producing a downdraft of air within the space surrounded by such annulus and in the vicinity of the portion of the fuel-heating tube passing through such space.

5. A liquid fuel burner comprising in combination a shell inclosing an initial combustion chamber, said shell having in its lower portion air inlet ports and a burner orifice and having in its upper portion a flame orifice, a flame deflector having a top above such shell, and having sides extending downward from said top, and arranged to convert the flame into an annulus, a fuel-heating tube passing through the space above such deflector; means for conveying gas from said fuel-heating tube to said burner orifice; and means for supplying liquid fuel to said fuel-heating tube.

6. A liquid fuel burner comprising in combination a shell inclosing an initial combustion chamber, said shell having in its lower portion air inlet ports and a burner orifice and having in its upper portion a flame orifice, a flame deflector having a top above such shell, and having sides extending downward from said top, and arranged to convert the flame into an annulus, a fuel-heating tube passing through the space above such deflector; means for conveying gas from said fuel-heating tube to said burner orifice, and means for supplying liquid fuel to said fuel-heating tube, said deflector provided in its upper portion with air admission ports.

7. A liquid fuel burner comprising in combination a shell inclosing an initial combustion chamber, said shell having in its lower portion air inlet ports and a burner orifice and having in its upper portion a flame orifice, a bell-shaped flame deflector above such shell having downwardly-extending sides, said deflector arranged to convert the flame into an annulus, a fuel-heating tube passing through the space above such bell-shaped deflector, means for conveying gas from said fuel-heating tube to said burner orifice, and means for supplying liquid fuel to said fuel-heating tube, said deflector provided in its upper portion with air-admission ports.

8. A liquid fuel burner comprising in combination a shell inclosing an initial combustion chamber, said shell having in its lower portion air inlet ports and a burner orifice and having in its upper portion a flame orifice, a flame deflector above such shell having downwardly extending sides,

said deflector arranged to convert the flame into an annulus, a fuel-heating tube passing through the space above such deflector, means for conveying gas from said fuel-heating tube to said burner orifice, and means for supplying liquid fuel to said fuel-heating tube, and a further flame-deflector surrounding said first-named deflector and arranged to cause the flame to spread out 10 still more widely.

9. A liquid fuel burner comprising in combination a shell inclosing an initial combustion chamber, said shell having in its lower portion air inlet ports and a burner orifice and having in its upper portion a flame orifice, a flame deflector above such shell having downwardly extending sides, said deflector arranged to convert the flame into an annulus, a fuel-heating tube passing 20 through the space above such deflector, means for conveying gas from said fuel-heating tube to said burner orifice, and means for supplying liquid fuel to said fuel-heating tube, said deflector provided in its upper portion with air-admission ports, and a contracting draft-director located above said deflector and arranged to direct a downwardly flowing current of air toward the air admission ports of said deflector.

30 10. A fuel burner comprising in combination a shell inclosing an initial combustion chamber, said shell having in its lower portion air inlet ports and a burner orifice and having in its upper portion a flame orifice, a flame deflector above such shell, and arranged to direct the flame downwardly from said flame orifice, and to convert the flame into an annulus, said deflector provided with air admission ports, and a contracting draft-director located above said deflector and arranged to direct a downwardly flowing current of air toward the air admission ports of said deflector, said draft-director having in its lower part an outwardly extending portion forming an additional flame deflector, whereby the flame passing beneath the lower edge of the first-named deflector is spread out yet more widely.

50 11. A liquid fuel burner comprising in combination a shell inclosing an initial combustion chamber, said shell having in its lower portion air inlet ports and a burner orifice and having in its upper portion a flame orifice, a flame deflector above such shell and arranged to direct the flame downwardly from said flame orifice and to convert the flame into an annulus, said deflector provided with air admission ports, a contracting draft-director located above said deflector and arranged to direct a downwardly flowing current of air toward the air admission ports of said deflector, said draft-director having in its lower part an outwardly extending portion

70 forming an additional flame deflector, whereby the flame passing beneath the lower edge of the first-named deflector is spread out yet more widely, a fuel-heating tube passing through the space above said first-named deflector and said draft-director, means for conveying gas from said fuel-heating tube to said burner orifice, and means for supplying liquid fuel to said fuel-heating tube.

75 12. A burner comprising in combination a shell inclosing an initial combustion chamber, said shell having in its lower portion air inlet ports and a burner orifice and having in its upper portion a flame orifice, a flame deflector above such shell having downwardly extending sides, said deflector arranged to spread out the flame and convert it into an annulus, and a further flame deflector located within said first-named deflector and removably secured thereto, and also located above said flame orifice.

80 13. A burner comprising in combination a shell inclosing an initial combustion chamber, said shell having in its lower portion air inlet ports and a burner orifice and having in its upper portion a flame orifice, a flame deflector above such shell having downwardly extending sides, said deflector arranged to spread out the flame and convert 85 it into an annulus, said deflector having air admission ports in its upper part, and a further flame deflector located within said first-named deflector and removably secured thereto, and also located above said flame 90 orifice, said second deflector also having air admission ports.

95 14. A burner comprising a shell inclosing an initial combustion chamber, said shell proportioned as to breadth for combustion 105 within it and formed in two parts, the lower of which has a burner orifice and air inlet ports, the upper portion of which shell rests removably upon the lower portion and is provided with a flame orifice, and a flame 110 deflector above said flame orifice and provided with a depending portion extending outside said shell below the center of said flame orifice and adapted to direct the flame 115 downwardly and outwardly.

15. A burner comprising a shell inclosing an initial combustion chamber, said shell formed in two parts, the lower of which has a burner orifice and air inlet ports, and is provided with a projecting flange forming a 120 burner-platform, the upper portion of which shell rests removably upon said lower portion and is provided with a flame orifice, and a flame deflector above said flame orifice, and provided with a depending portion extending below the center of said flame orifice 125 and adapted to direct the flame downwardly and outwardly.

16. A burner comprising a shell inclosing an initial combustion chamber, said shell 130

formed in two parts, the lower of which has a burner orifice and air inlet ports, the upper portion of which shell rests removably upon said lower portion and is provided with a flame orifice, the axis of said flame orifice located to one side of the axis of the shell.

17. A burner comprising a shell inclosing an initial combustion chamber, said shell formed in two parts, the lower of which has a burner orifice and air inlet ports, the upper portion of which shell rests removably upon said lower portion and is provided with a flame orifice, the axis of said flame orifice located to one side of the axis of the shell, and a flame deflector above said shell and arranged to deflect the flame issuing from said orifice downward and thence outward in the form of an annulus.

18. A burner comprising a shell inclosing an initial combustion chamber, said shell formed in two parts, the lower of which has a burner orifice and air inlet ports, and is provided with a projecting flange forming a burner-platform, the upper portion of which shell rests removably upon said lower portion and is provided with a flame orifice, and a flame deflector above said shell and having sides extending downward into proximity to said platform and arranged to cause the flame issuing from said flame orifice to pass between the lower edge of said deflector and the said burner-platform.

19. A burner comprising a shell inclosing an initial combustion chamber, said shell formed in two parts, the lower of which has a burner orifice and air inlet ports, and is provided with a projecting flange forming a burner-platform, the upper portion of which shell rests removably upon said lower portion and is provided with a flame orifice, a flame deflector above said shell and having sides extending downward into proximity to said platform and arranged to cause the flame issuing from said flame orifice to pass between the lower edge of said deflector and the said burner platform, and a further flame deflector above said first-mentioned deflector, and having an outwardly extending and downwardly-extending lower portion arranged to spread the flame yet more widely.

20. A burner comprising in combination a shell inclosing an initial combustion chamber, said shell having air inlet ports and a burner orifice and having in its upper portion a flame orifice, said shell further provided with an outwardly extending ported burner platform, a deflector above said flame orifice arranged to deflect the flame downwardly toward said platform and thence outwardly and a water trough beneath said platform and supported thereby and arranged to mingle water vapor with the flame and draft currents of the burner.

21. A burner comprising in combination a

shell inclosing an initial combustion chamber, said shell having in its lower portion air inlet ports and a burner orifice, and having in its upper portion a flame orifice, said shell further provided with an outwardly extending burner platform, a flame deflector above said shell arranged to deflect the flame from said orifice downwardly and outwardly, and a foraminous flame-guard inclosing the flame-space outside of said flame-deflector, and above said platform.

22. A burner comprising in combination a shell inclosing an initial combustion chamber, said shell having in its lower portion air inlet ports and a burner orifice, and having in its upper portion a flame orifice, said shell further provided with an outwardly extending burner platform, a flame deflector above said shell arranged to deflect the flame from said orifice downwardly and outwardly, and a plurality of foraminous flame guards located one within another, and inclosing the flame-space outside of said flame-deflector.

23. A burner comprising in combination a shell inclosing an initial combustion chamber, said shell having air inlet ports and a burner orifice and having in its upper portion a flame orifice, a bell-shaped flame-deflector above said shell, said flame deflector having in its upper portion air-admission ports, and having in its upper external surface channels leading to said ports, and a contracting draft-director resting upon said flame deflector.

24. A burner comprising a burner tip having a burner orifice, means for conveying gas to such orifice, flame-guarding and flame-deflecting means comprising means completely inclosing an initial combustion-chamber through which the jet from such burner orifice passes, and comprising also deflecting means arranged to convert the jet into an annulus and to deflect the same downwardly and outwardly, and a fuel-heating tube, connected to said gas-conveying means, and located in the main above said flame deflecting means.

25. A burner comprising a burner tip having a burner orifice, means for conveying gas to such orifice, a flame-guarding and flame-deflecting structure comprising means completely inclosing an initial combustion-chamber through which the jet from such burner orifices passes, and comprising also deflecting means arranged to convert the jet into an annulus and to deflect the same downwardly and outwardly, such structure provided with air ports leading to the initial combustion chamber, and a fuel-heating tube, connected to said gas-conveying means, and located in the main above said flame deflecting means.

26. A burner comprising a burner tip having a burner orifice, means for conveying

gas to such orifice, a flame-guarding and flame-deflecting structure comprising means completely inclosing an initial combustion-chamber through which the jet from such 5 burner orifice passes, and comprising also deflecting means arranged to convert the jet into an annulus and to deflect the same downwardly and outwardly, such structure provided with air ports leading to the initial 10 combustion chamber, and with air ports leading into the interior of the flame-deflecting means, and a fuel-heating tube, connected to said gas-conveying means, and located in the main above said flame deflecting means.

27. A burner comprising a burner tip having a burner orifice, means for conveying gas to such orifice, a flame-guarding and flame-deflecting structure comprising means 20 completely inclosing an initial combustion-chamber through which the jet from such burner orifice passes, and comprising also deflecting means arranged to convert the jet into an annulus and to deflect the same 25 downwardly and outwardly, such structure provided with a port leading into the initial combustion chamber, and a starting burner arranged to project flame through such port into such initial combustion chamber, and a 30 fuel-heating tube, connected to said gas-conveying means, and located in the main above said flame deflecting means.

28. A burner comprising upwardly-directed flame-projecting means and a deflector thereabove comprising means arranged to deflect such flame downwardly and outwardly as an annulus, and a fuel-heating tube above said deflector and connected to said flame-projecting means.

40 29. A burner comprising upwardly-directed flame-projecting means and a deflector thereabove arranged to deflect such flame downwardly and outwardly as an annulus, said deflector provided with air admission means through which air may be drawn in to mingle with the flame, and a fuel-heating tube above said deflector and connected to said flame-projecting means.

50 30. A burner comprising upwardly-directed flame-projecting means, a deflector thereabove arranged to deflect such flame downwardly and outwardly as an annulus, a fuel-heating tube above said deflector and connected to said flame projecting means, and a platform beneath said deflector arranged to spread the flame annulus outwardly.

55 31. A burner comprising upwardly-directed flame-projecting means, a deflector thereabove arranged to deflect such flame downwardly and outwardly as an annulus, and a platform beneath said deflector arranged to spread the flame annulus outwardly, both said flame deflector and said 60 platform provided with air admission means

through which air may be drawn in to mingle with the flame.

32. A burner comprising upwardly-directed flame-projecting means, a deflector thereabove arranged to deflect such flame 70 downwardly and outwardly as an annulus, and a platform beneath said deflector arranged to spread the flame annulus outwardly, both said flame deflector and said platform provided with air admission means 75 through which air may be drawn in to mingle with the flame, and a water trough wherein water may be evaporated to produce vapor to mingle with the air and flame currents of the burner.

80 33. A burner comprising upwardly-directed flame-projecting means, a guard which surrounds the space above such flame-projecting means, a deflector above said guard and arranged to deflect the flame 85 downwardly and outwardly as a flame annulus surrounding a portion of said guard, and a fuel-heating tube above said deflector and connected to said flame projecting means.

90 34. A burner comprising upwardly-directed flame-projecting means, a guard which surrounds the space above such flame-projecting means, a deflector above said guard and arranged to deflect the flame 95 downwardly and outwardly as a flame annulus surrounding a portion of said guard, said deflector having air admission means through which air may be drawn in to mingle with the flame.

100 35. A burner comprising upwardly-directed flame-projecting means, a guard which surrounds the space above such flame-projecting means, a deflector above said guard and arranged to deflect the flame 105 downwardly and outwardly as a flame annulus surrounding a portion of said guard, said deflector having air admission means through which air may be drawn in to mingle with the flame, and a platform beneath said 110 deflector and likewise provided with air admission means.

115 36. A burner comprising upwardly-directed flame-projecting means, a guard which surrounds the space above such flame-projecting means, a deflector above said guard and arranged to deflect the flame 120 downwardly and outwardly as a flame annulus surrounding a portion of said guard, said deflector having air admission means through which air may be drawn in to mingle with the flame, and a platform beneath 125 said deflector and likewise provided with air admission means, and a water trough wherein water may be evaporated to produce vapor to mingle with the air and flame currents of the burner.

37. A burner comprising upwardly-directed flame-projecting means, a deflector thereabove arranged to deflect the flame 130

downwardly and outwardly as a flame annulus, a platform beneath said deflector and screws mounted in said platform and upon which said deflector rests, said screws constituting means whereby the height of said deflector may be varied.

38. A burner comprising in combination flame-projecting means, a flame deflector in the path of flame projected from such flame-projecting means, said deflector arranged to direct the flame backwardly and outwardly as an annulus, and a flame-guard

which surrounds the space between said flame-projecting means and said deflector, said flame guard having a flame orifice located to one side of the axis of said flame-projecting means. 15

In testimony whereof I have signed this specification in the presence of two subscribing witnesses.

THOMAS B. FERGUSON.
